UNITED STATES PATENT OFFICE.

EMILE MAERTENS, OF PROVIDENCE, RHODE ISLAND.

PROCESS OF AND APPARATUS FOR EXTRACTING FAT.

SPECIFICATION forming part of Letters Patent No. 615,030, dated November 29, 1898.

Application filed December 28, 1897. Serial No. 663,902. (No model.)

To all whom it may concern:

Be it known that I, EMILE MAERTENS, a citizen of the United States, residing at Providence, in the county of Providence and State 5 of Rhode Island, have invented certain new and useful Improvements in Processes of and Apparatus for Treating Raw Wool and other Materials with Volatile Solvents, (for which I have obtained a patent in Germany, No. 10 93,743, dated August 30, 1897; in Austria, No. 47/3,308, dated September 10, 1897, and in Hungary, No. 8,763, dated July 31, 1897;) and I do hereby declare the following to be a 15 full, clear, and exact description of the invention, such as will enable others skilled in the art to which it appertains to make and use the same, reference being had to the accompanying drawings, and to letters of reference marked thereon, which form a part of this 20 specification.

The invention forming the subject of my present application for Letters Patent relates to improvements in apparatus for and processes of extracting from raw wool and other 25 materials by means of suitable volatile solvents the resinous, oily, essential, fatty, and other similar matters associated therewith, said invention being an improvement on the processes and apparatus described and 30 claimed by me in my United States Letters Patent dated September 10, 1895, and numbered 545,899 and 545,900.

The present invention relates more essentially to the economical removal and saving 35 of the solvent adhering to the materials after their extraction, and more particularly to the economical and safe treatment of wool and similar fibers with volatile solvents.

In a process of degreasing wool according 40 to my invention the fibers are treated in closed digesters until the complete extraction with the volatile solvent employed is effected, some of the principal new features of said process being as follows: I employ a gas which 45 is contained in a holder. It is withdrawn from said holder for use and returned to the holder after such use to be repeatedly reused. The gas employed is compressed and used as a forcing or motive power or agent to 50 circulate the solvents through the fibers under treatment. It is used to press the liquid solvent out of the fibers as well as to blow

out of them such solvent as has not been removed by pressure. It is used as a heat-carrying medium to the fibers and as a solvent 55 vapor-carrying medium from the fibers. It is used as an atmosphere wherein to carry on the extracting operation, for covering the solvent in the reservoirs, and for taking the place of the solvent removed from any of the 60 elements forming part of the apparatus, and thus prevents the ignition of the solvent vapors by the electric or other spark which may accidentally be communicated to it, and since the gas is always moved in a closed circuit it 65 prevents the loss of solvent vapors, and it can be used repeatedly without limit.

I would explain that the gas just referred to as being employed in my improved process is an inert gas or a gas which does not form 70 explosive compounds with the vapors of the solvents used or with atmospheric air—such, for example, as nitrogen or carbonic-acid gas. Hydrogen, illuminating-gas, and even atmospheric air can be used so far as the carrying 75 out of the process is concerned; but hydrogen and carbureted hydrogen are less desirable on account of their inflammability and explosive properties when mixed with air, and even atmospheric air makes a very 80 dangerous and explosive compound when mixed with the vapors of the solvents employed in certain proportions, and it is therefore an undesirable and unsafe agent to use. Consequently without limiting myself to the 85 use of any particular or specific gas or mixture of gases for carrying out my improved process I prefer and recommend the employment of inert gases or mixtures of such gases.

In the accompanying two sheets of drawings, which combined form a single figure representing a side elevation, in partial section, of a plant capable of performing the functions forming the subject of my present invention, A indicates a gas-holder. 90

B is a gas-compressor.

C is an exhauster or vacuum-pump.

D is a blower or a rotary and positive gas or air circulating pump.

E is a condenser wherein the cooling medium is water. 100

F is a heater, the heating medium being steam.

G is a four-way valve used for reversing

the direction of motion of the circulating gas through the digesters.

II is a trap-tank forming a water seal between the gas in the holder and the rest of the system.

I and I' are digesters wherein the wool or fibers are treated, as in extracting the grease, &c.

J, J', and J² are storage-tanks for solvents of different degrees of purity or saturation.

K is an overflow-tank through which the compressed gas when liberated from any of the digesters or tanks returns to the holder. It also serves as a catch-basin for any liquid solvent carried along with the gas or for any solvent which might accidentally overflow from the digesters or storage-tanks.

L is a separating-tank wherein the water coming from the steam used in the treating process or from the fibers is separated from the solvent.

M is a suction or vacuum main communicating with the suction ends of the exhauster C and blower D, but which (through the branch M', four-way valve G, heater F, condenser E, valve i³, and pipe N²) can also be made to communicate with the discharge end of the blower D.

N is a discharge or pressure main communicating with the discharge end of the blower, but which can also be put in communication with the suction end of said blower by the branch N', four-way valve, pipe N⁴, and valve h³ and in communication with the atmosphere through branches N³ and N⁵.

O is a main supplying compressed gas to the system.

P is a main leading any liberated gas back to the holder.

Q is a main communicating with the storage-tanks and for supplying solvent to the digesters.

R is a main communicating with the storage-tanks and receiving the returned or used solvent from the digesters.

S is a top connection located between and uniting the digesters, thereby allowing the escape of gas from one digester into the other when desirable.

T is a pipe through which gas from the holder A is admitted into the system via pipe P.

U is a pipe for conveying condensed vapors from the condenser E and suction end of blower D to tank L.

V is a pipe for supplying the compressor B with gas from the holder A.

W is a pipe adapted to convey condensed solvent from the surface of the water in the gas-holder tank into tank L.

X X are the doors through which the digesters are filled.

Y Y are the doors through which the digesters are emptied.

Z is a pipe leading from the storage-tanks to the distillery, where the wool-fat is recovered from the solvent.

The following is a description of the operation of the apparatus: The digesters I and I' having been filled with wool through the upper openings or necks of the digesters, the several doors X and Y are then hermetically closed, and in order to make a vacuum in the digesters the latter are put into communication with the exhauster C, (through valves h

70

h', main M, and valve t²,) thereby withdrawing the air from the digesters and discharging it into the atmosphere by the exhauster C, via valve a.

Now when a vacuum of about twenty-eight or twenty-nine inches of mercury has been obtained the exhauster is

80

stopped and all the valves previously opened are closed. The solvent from tank J (which contains solvent having considerable wool-fat in solution) is brought into digester I by

85

opening valves b and c, thus establishing communication between the tank and digester and at the same time starting compressor B,

followed by opening valve e, thereby allowing compressed gas to enter tank J and force its

90

contents into digester I. When the latter is full of solvent, (which is shown by a gage-glass,) the valves previously opened are

95

closed and valve d opened and the compressed gas in tank J escapes back to the holder A via main P and tanks K and II.

In order to

force the solvent contained in digester I into digester I' and replace the solvent in digester I by the solvent contained in tank J', (which is slightly impregnated with wool-fat from

100

use in previous operations,) communication is established between compressor B and tank J' by opening valve e'. Valves b' and c are

105

also opened, and when pressure appears on the pressure-gage of digester I the latter is put into communication at its bottom with the top of digester I' by opening valve c',

110

thereby allowing the solvent contained in digester I to be diverted to the top of digester I', whereas the solvent contained in tank J' fills digester I.

115

When the digester I' is full, valves b' and e' are closed, the compressor B stopped, and valve d' opened, thus allowing the compressed gas contained in tank J' to escape to the holder A via main P and tanks

120

K and II. Now to rinse the wool or material under treatment with pure solvent tank J² (which contains the latter) is put into communication with the compressor B (which is

125

now started) by opening valve e². The valve b³ is also opened, and as soon as pressure shows on the gages of the digesters the bottom of digester I' is put into communication with tank J by opening valves f' and l, and the

130

clean solvent from tank J² enters digester I, while the solvent which was contained in the latter digester escapes from its bottom into the top of digester I' and the solvent contained in digester I' escapes through its bottom into the tank J.

135

After a quantity of solvent equal to more than the contents of digester I' has been let into the tank J the valve l' is opened. This allows the solvent then contained in digester I' and which in part origi-

nally came from tank J' to re-enter this latter tank mixed with a quantity of what was originally pure solvent. By the time tank J' is full the tank J² will be empty of its solvent 5 as well as digester I, and digester I' will only contain a small amount of practically pure solvent. The compressor B is then stopped, valve l' closed, as well as valves c, c', and e', and valves l², d², and f are opened. The gas 10 contained in tank J² escapes to the holder via main P, valve d², and tanks K and H, while the solvent still contained in digester I' and that which may drip from digester I enters tank J². Now in order to squeeze out the 15 bulk of the solvent still retained by the wool valves f and f' are closed and valves g and g' opened. The compressor B is then started and a strong gas-pressure is accumulated on top of the material contained in the digesters. 20 By means of the thus compressed gas and the quick opening of valves f and f' the greater portion of the solvent retained by the fibers is expressed and run into the tank J². This last operation is repeated once or twice and 25 then compressed gas is allowed to blow for a few minutes through the material, thereby practically removing all the solvent which can be eliminated from the fibers in liquid form. It is of course understood that the gas 30 used for this purpose finds its way back to the holder A via tank J², valve d², main P, and tanks K and H. In order to eliminate the solvent still adhering to the fibers, all the valves previously opened are next closed and 35 the digesters are put into communication at their upper ends with the suction of the blower D through valves h h', main M, valve h², branch M', four-way valve G, pipe N⁴, and valve h³, the bottom of the digesters being put 40 in communication with the discharge or forcing end of said blower, which is now started, through valves i i', piping N, valve i², branch N', four-way valve G, heater F, condenser E, and valve i³, at the same time circulating cold 45 water through the condenser and steam through the heater, it being understood that the digesters, pipes, heater, condenser, and blower are filled with the gas forming the circulating medium. The gas discharged by the 50 blower is deprived of moisture and solvent vapors by passing it through the condenser. It is warmed or heated by passing it through the heater. It enters the digesters in a dry state at their lower ends. It saturates itself 55 with solvent vapors while passing upwardly through the wool or material in the digesters, such upward movement of the gas being effected by the partial vacuum existing at the top of the digesters and caused by the suction 60 of the blower D and the resistance of the wool in the digesters. As soon as the solvent vapor-laden gas has passed from the blower into the condenser it is stripped of all the solvent and moisture it has absorbed, is then reheated 65 and repassed through the wool, the operation being continued in this unbroken circuit or cycle until it has deprived the wool of all

the volatilizable solvent which it contained. During the circulation of gas through the fibers, as just described, and in order to 70 maintain their proper hygrometric condition a small jet of steam is admitted in the current by pipes provided for the purpose, and that the contents at both ends of the digesters may receive as near as possible the same 75 amount of heat the four-way valve G has been provided. By turning the wing of this valve one-fourth way around at stated intervals of time the suction and discharge of the blower D from and to the top and bottom of the digesters are alternated and an unequal treatment of the different parts of the digesters is thus avoided. The solvent and water vapors withdrawn from the fibers, and which condense in the blower and condenser, run 80 through valves k and k' into pipe U and from the latter into tank L. A small cock u', placed in pipe u, is used as a telltale to indicate when the solvent vapors have ceased coming over, thus indicating to the attendant that 85 the drying or solvent-removing operation is completed. When this is accomplished, the gas is removed from the digesters, pipes, &c., and for this purpose the blower D is stopped, the valves i², h², i³, h³, and k are closed, and 90 valves t' and t² on pipe leading to and from exhauster C are opened, at the same time opening valve d⁴ in the gas-escape pipe leading from tank L. The vacuum-pump C is 95 now started, by means of which the gas contained in the digesters and pipes (as well as any remnants or traces of solvent which may accidentally have been left in the wool and which is volatilized under the influence of the heat in the material and the high vacuum 100 produced) is withdrawn from that part of the system and returned to the gas-holder A via valve t', condenser E, tank L, main P, and tanks K and H. When a sufficiently high vacuum has been obtained, the pump C is 105 stopped and all the valves previously open (except i, i', h, and h') are closed. The wool being now freed from solvent and in a dry condition and the digesters having been freed from gas, atmospheric air is next let into the 110 two digesters by opening the valve m' of the air-pipe N⁵. The digesters themselves are then again put into communication with the blower D, which is started and made to discharge into the atmosphere through valve m. 115 Finally, atmospheric air mixed with steam (admitted into pipe N through suitable connections) is now circulated through the contents of the digesters for two or three minutes, after which the wool or material with 120 which the digesters is charged will be found in proper condition to be removed from them. This may be effected after closing all the valves and stopping the blower D through the 125 digester-doors Y.

130

I claim as my invention—

1. In the art of removing solvent or residual solvent from fibrous and other materials containing the same, the improvement which

consists in passing a suitable gas through the material, then freeing the gas wholly or in part from the solvent which it has absorbed, and finally reusing the gas substantially as 5 described.

2. In the art of removing solvent or residual solvent from fibrous and other materials containing the same, the improvement which consists in first heating a suitable gas, then 10 passing it through the said material, then cooling the gas whereby it is freed wholly or in part from solvent, and then conducting the gas to a suitable holder substantially as described.

15 3. In the art of removing solvent or residual solvent from fibrous and other materials containing the same, the improvement which consists in passing a suitable gas through the material, circulating said gas in a closed circuit, freeing it wholly or in part from the solvent which it has absorbed, on its way 20 from and before its return through the material substantially as described.

4. In the art of removing solvent or residual 25 solvent from fibrous and other materials containing the same, the improvement which consists in passing a suitable gas through the material, circulating said gas in a closed circuit, heating it on its way through the material so as to make its absorbent capacity 30 greater and cooling it on its way from the material so as to free it wholly or in part from solvent, substantially as described.

5. In the art of removing solvent or residual 35 solvent from fibrous and other materials containing the same, the improvement which consists in circulating through the material a suitable gas, which is drawn from a holder and is returned to said holder after use, substantially as described.

40 6. In the art of removing solvent or residual solvent from fibrous and other materials containing the same, the improvement which consists in the employment of a suitable gas or mixture of gases, drawn from a holder and used to form an atmosphere above the solvent in the reservoirs, hereinbefore described, to circulate the liquid solvent through the material being treated, to form a heat-carrying 45 medium to the material and to serve as a solvent-vapor-carrying agent from said material, and after being devaporized wholly or in part, is returned to the holder and is adapted to be repeatedly reused, substantially as 50 described.

55 7. In apparatus used in the art of extracting matters from fibrous or other materials with volatile solvents and of removing solvent or residual solvent therefrom, the combination of one or more digesters, one or more reservoirs for solvents, a vacuum-pump arranged to pump air or gas out of the system into the atmosphere or to circulate the same through the system and suitably-connected 60 valved piping for circulating the solvent air or gas substantially as described.

65 8. In apparatus used in the art of extract-

70 ing matters from fibrous or other materials with volatile solvents and of removing solvent or residual solvent therefrom, the combination of one or more digesters, one or more reservoirs for the solvent, a gas-holder, a vacuum-pump arranged to pump air or gas out of the system into the atmosphere or into the gas-holder or to circulate the same through the system, 75 the system and suitably-connected valved piping for circulating the solvents and air or gas and for carrying the gas from the holder to the digesters, reservoirs, &c., and for returning it to said holder, substantially as described.

90 9. In apparatus used in the art of extracting matters from fibrous or other materials with volatile solvents and of removing solvent or residual solvent therefrom, the combination of one or more digesters, one or more reservoirs, for the solvents, a vacuum-pump arranged to pump air or gas out of the system into the atmosphere or into the gas-holder or to circulate the same through the system, 95 a gas-compressor and suitably-connected valved piping for circulating the solvent and air or gas and for carrying the gas from the holder to the digesters, reservoirs, &c., and for returning it to said holder, substantially as described.

100 10. In apparatus used in the art of extracting matters from fibrous or other materials, with volatile solvents and of removing solvent or residual solvent therefrom, the combination of one or more digesters, one or more reservoirs for solvents, a vacuum-pump arranged to pump air or gas out of the system into the atmosphere or into the gas-holder or to circulate the same through the system, a 105 gas-compressor, a condenser and suitably-connected valved piping for circulating the solvent and air or gas and for carrying the gas from the holder to the digesters, reservoirs, compressor, &c., and for returning it to said holder substantially as described.

110 11. In apparatus used in the art of extracting matters from fibrous or other materials with volatile solvents and of removing solvent or residual solvent therefrom, the combination of one or more digesters, one or more reservoirs for the solvents, a gas-holder, a 115 vacuum-pump, a gas-compressor, a condenser, a heater, and suitably-connected valved piping for circulating the solvent and air or gas 120 and for carrying the gas from the holder to the digesters, reservoirs, compressor, &c., and for returning it to said holder substantially as described.

125 12. In apparatus used in the art of extracting matters from fibrous or other materials with volatile solvents and of removing solvent or residual solvent therefrom, the combination of one or more digesters, one or more reservoirs for solvents, a gas-holder, a vacuum-pump, a gas-compressor, a condenser, a heater, a blower, and suitably-connected valved piping for circulating the solvent and air or gas 130 and for carrying the gas from the holder to

the digesters, reservoirs, compressor, &c., and for returning it to said holder substantially as described.

13. In apparatus used in the art of extracting matters from fibrous or other materials with volatile solvents and of removing solvent or residual solvent therefrom, the combination of one or more digesters, one or more reservoirs for the solvent, a gas-holder, a vacuum-pump, a gas-compressor, a condenser, a heater, a blower, a four-way valve, and suitably-connected valved piping for circulating the solvent and air or gas and for carrying the gas from the holder to the digesters, reservoirs, compressor, &c., and for returning it to said holder, substantially as described.

14. In apparatus used in the art of extracting matters from fibrous or other materials with volatile solvents and of removing solvent or residual solvent therefrom, the combination of one or more digesters, one or more reservoirs for the solvents, a gas-holder, a vacuum-pump, a gas-compressor, a condenser, a heater, a blower, a four-way valve, a trap-tank, and suitably-connected valved piping for circulating the solvent and air or gas and for carrying the gas from the holder to the digesters, reservoirs, compressor, &c., and for returning it to said holder, substantially as described.

15. In apparatus used in the art of extracting matters from fibrous or other materials with volatile solvents and of removing solvent

or residual solvent therefrom, the combination of one or more digesters, one or more reservoirs for the solvents, a gas-holder, a vacuum-pump, a gas-compressor, a condenser, a heater, a blower, a four-way valve, a trap-tank, an overflow-tank and suitably-connected valved piping for circulating the solvent and air or gas and for carrying the gas from the holder to the digesters, reservoirs, compressor, &c., and for returning it to said holder, substantially as described.

16. In apparatus used in the art of extracting matters from fibrous or other materials with volatile solvents and of removing solvent or residual solvent therefrom, the combination of one or more digesters, one or more reservoirs for the solvents, a gas-holder, a vacuum-pump, a gas-compressor, a condenser, a heater, a blower, a four-way valve, a trap-tank, an overflow-tank, a separating-tank, and suitably-connected valved piping for circulating the solvent and air or gas and for carrying the gas from the holder to the digesters, reservoirs, compressor, &c., and returning it to said holder, substantially as described.

In testimony whereof I have affixed my signature in presence of two witnesses.

EMILE MAERTENS.
